UNITED STATES PATENT OFFICE.

CHARLES C. BROWN, OF MACON, GEORGIA.

WASTE-RECEPTACLE.

1,237,016.

Specification of Letters Patent. Patented Aug. 14, 1917.

Application filed September 6, 1916. Serial No. 118,653.

To all whom it may concern:

Be it known that I, CHARLES C. BROWN, a citizen of the United States, and resident of Macon, in the county of Bibb and State 5 of Georgia, have invented a new and Improved Waste-Receiptacle, of which the following is a full, clear, and exact description.

My invention relates to a receptacle for receiving ashes, refuse, garbage, or any sort 10 of waste material.

The object of my invention is to provide a waste receptacle which will automatically close after using, thus retaining any dust arising from the deposit of ashes or other 15 material of like nature, and preventing the escape of noxious odors from the refuse and garbage placed therein.

A further object of my invention is to provide a receptacle for holding waste matter 20 which can be placed out of doors to be emptied by the scavengers without danger of the contents and the inside of the receptacle becoming wet in case of rain.

Lastly, it is my object to make a receptacle 25 which will be tightly closed, so that the contents will be inaccessible to flies, etc., and will be retained without spilling while being removed, thus insuring a clean and sanitary disposal of waste matter.

In carrying out the objects above enumerated, I employ in the preferred embodiment 30 of my invention the form of receptacle and mechanism illustrated in the accompanying drawings, in which similar reference characters refer to corresponding parts throughout the several views.

Figure 1 is a view in elevation of the top portion of the receptacle.

Fig. 2 is a top view of the receptacle with 40 a part thereof shown in section.

Fig. 3 is a side elevation of the receptacle.

Fig. 4 is an enlarged sectional view through the cover of the receptacle on the line 4-4 of Fig. 2.

Fig. 5 is an enlarged sectional view on the line 5-5 of Fig. 1.

The body of the receptacle 1 is a common form of garbage can provided with side handles and having longitudinal guards extending to within a short distance of the top and bottom of the can, but the top opening of the receptacle, instead of being in a plane parallel with the plane of the base, lies in a plane inclined to the plane of the

base, and making an angle therewith of approximately 30 degrees.

Upon the lower portion of the top edge of said body, I provide a roll or flange 2 designed to receive and interlock with the upturned flange 3 on the periphery of the cover.

The cover 4 also carries a downwardly projecting circumferential flange 5 adapted to overlap and snugly fit the upper edge of the body of the receptacle.

It will be noted that the depending flange 5 is situated to the right of the axial supporting means 7 shown in Fig. 3, and the body flange 3 extends to the left of said supporting means, said flanges, together with the cover 4, uniting to form a waterproof top for said receptacle.

Fitted in sockets 6 attached to the upper portion of the inner face of the receptacle body 1, or by other suitable means, is a rod 7 on which the receptacle cover is axially mounted by means, such, for example, as straps 8.

The flange 3 on the cover 4 is broken at 9 to provide an aperture for draining off water collecting on the cover, said aperture 9 being in registry with an aperture 10 located at the lowermost point of the inclined top opening and through the wall of the body 1.

In order to bring about the automatic closing of the cover 4, after the material is deposited in the receptacle, I position the cover 4 on rod 7 in such a manner that the rod 7 does not pass through the center of gravity of the cover, but is eccentrically fastened on that side of the center of the cover nearer the lower edge of the incline, thus distributing more weight on the upper side of the axial line of support of cover 4.

It is obvious that the automatic closing action of the cover may be attained by means other than those described, as, for example, rod 7 may be positioned through the center of gravity of said cover and a counterweight 100 may be attached to the upper portion of said inclined cover falling to the right of the axial support shown in Fig. 3.

In using my waste receptacle, the material may be deposited therein by manually 105 depressing the lower portion of the inclined cover, or it will be perceived that the weight of the material may frequently be suffi-

ciently great to overbalance the counter-weight, tending to close the cover of the receptacle, in which case the material may be emptied on the cover from which it will 5 descend into the receptacle by gravity, automatically opening said cover, the roll or flange 2 serving to retain the material in place on the cover before the opening thereof, and preventing the overflow of material 10 while sliding from said cover into the receptacle.

When exposed to rain, the interior of the receptacle and contents are kept dry by means of flanges 2 and 5, and the water, as 15 fast as it falls on the inclined cover, is collected by the flange 3 conducted through the apertures 9 and 10, and discharged outside the receptacle.

Having thus described my invention, I 20 claim as new and desire to secure by Letters Patent:

1. A waste receptacle having a cover axially mounted in and normally closing the top opening thereof, and extending upon 25 both sides of the axial line of support, the area of said cover on one side of the axial line of support being greater than the area on the other side thereof, the periphery of the greater area being provided with a 30 downturned flange adapted to engage the exterior of the upper edge of the wall of the receptacle, and the periphery of the smaller area fitting within the opening of the receptacle.

35 2. A waste receptacle having a cover axially mounted in and normally closing the top opening thereof, and extending upon both sides of the axial line of support, the area of said cover on one side of the axial 40 line of support being greater than the area on the other side thereof, the periphery of the greater area contacting with the upper edge of the wall of the receptacle, and the periphery of the smaller area provided with 45 an upturned flange interlocking with a roll or flange on the upper edge of the wall of the receptacle.

50 3. A waste receptacle having a cover axially mounted in and normally closing the top opening thereof, and extending upon both sides of the axial line of support, the area of said cover on one side of the axial line of support being greater than the area on the other side thereof, the periphery of 55 the greater area being provided with a downturned flange adapted to engage the exterior of the upper edge of the wall of the receptacle, and the periphery of the smaller

area provided with an upturned flange interlocking with a roll or flange on the upper 60 edge of the wall of the receptacle.

4. A waste receptacle having a top opening in a plane inclined to the plane of the base, a cover normally closing the receptacle axially mounted in the top opening thereof, 65 and extending upon both sides of the axial line of support, the area of said cover on one side of the axial line of support being greater than the area on the other side thereof, the periphery of the greater area 70 of said cover contacting with the upper edge of the wall of the receptacle, and the periphery of the smaller area of the cover fitting within said opening.

5. The combination with a waste receptacle having its open end in a plane inclined to the plane of the base, of a cover axially mounted in said opening and extending upon both sides of the axial line of support, 75 the cover being heavier at one side of the axial line of support than at the other side, and means for draining said cover.

6. The combination of a waste receptacle having its open end in a plane inclined to the plane of the base, of a cover axially 80 mounted in said opening and extending upon both sides of the axial line of support, the area of the cover at one side of the axial line of support being greater than the area at the other side, and means for draining 90 said cover.

7. The combination with a waste receptacle having its top opening in a plane inclined to the plane of the base, of a cover for said opening axially mounted in the body of said receptacle, flanges on said cover and said body, apertures in the flange on said cover, and in said body coöperating to drain said cover.

8. A receptacle having its open end lying 100 in a plane inclined to the plane of the base, a cover normally closing said opening, axially and eccentrically mounted on a rod secured in the body of said receptacle, peripheral flanges carried by said cover, a flange 105 on the lower edge of said body opening, and an aperture in said cover flange in registry with an opening in the body of said receptacle, as and for the purposes set forth.

In testimony whereof I have signed my 110 name to the specification in the presence of two subscribing witnesses.

CHARLES C. BROWN.
